UNITED STATES PATENT OFFICE.

JOHN M. TAYLOR, OF BRIDGEPORT, PENNSYLVANIA, ASSIGNOR TO DIAMOND STATE FIBRE COMPANY, OF BRIDGEPORT, PENNSYLVANIA, A CORPORATION OF DELAWARE.

NOISELESS GEAR.

Application filed January 30, 1925. Serial No. 5,809.

This invention relates to noiseless gear and like construction, and more particularly to gears utilizing an artificial resin, such as bakelite, as the material affording the desired characteristic of comparative noiselessness. It is to be understood, however, that the invention is not restricted to the use of an artificial resin, since other substances may successfully be used instead. 10 The principal object of the invention is to provide a noiseless gear or like element having a novel and advantageous distribution of sound-reducing and other materials, affording economy of the former with an article of superior strength and durability. 15 Another object of the invention is to provide a noiseless gear comprising both metal and a noise-reducing material in novel and highly efficient combination. 20 Several embodiments of my invention are illustrated in the attached drawings, in which: 25 Figure 1 is a sectional perspective view of a gear blank made in accordance with my invention; 30 Figs. 2 and 3 are true vertical sections illustrating modifications within the scope of the invention, and Figs. 4 and 5 are, respectively, face views of two different forms of reinforcing element. 35 With reference to the drawings, and particularly to Fig. 1, I have illustrated a gear blank in which the hub portion 1 and the web 2 consist of a plurality of metal plates or disks 3 bound together through the said hub portion by bolts 4. Other forms of securing means may be employed, such as rivets or welding. 40 In the present instance, I prefer to employ face plates 5 on the faces of the hub, these plates constituting seats for the head of the bolt and for the nuts, and preventing mutilation of the disks 3. As clearly 45 illustrated, those of the disks 3 which form the web 2 are of sufficiently great diameter to extend into and through the rim portion 6 of the blank from the inner surface of the latter to the outer, the rim, however, being 50 of greater width than the web portion 2. The outer portions of the disk 3 are so bent or formed as to afford a preferably uniform distribution of these parts across the entire width of the rim, as clearly illustrated. The 55 outer rim portions of the disk 3 are perfo- rated, as indicated in Fig. 4, and are embedded in or laminated with a suitable material, such as artificial resin or fibrous material combined with an artificial resin capable of giving the gear the desired noiseless 60 characteristics. Although I prefer to use an artificial resin such as bakelite for this purpose, it will be understood, as previously stated, that natural resins and other substances may be found having the character- 65 istics requisite for such use. In the drawings, I have designated this material by the reference numeral 7, and by reason of the perforations in the outer rim portion of the disk 3, it will be apparent 70 that this material will be thoroughly bonded with the disks. Where an artificial resin is employed, it may be applied either in its initial or intermediate stage and subjected in the usual 75 manner to heat and pressure sufficient to convert it to its hard infusible final state. Instead of employing the unmixed resin, the latter may be combined with suitable fibrous material, and if desired, the rim portion may 80 consist of a laminated structure consisting of layers of paper or fabric impregnated with the artificial resin in its hard infusible state and interspersed with the metal 85 disks 3. Numerous modifications are possible without departure from the essential features of the invention, and several of such modifications are herein illustrated. Thus in Fig. 2 I have shown the hub portion 1 formed as previously described by laying together a number of suitably shaped metal disks, these being secured together by bolts 4 or other suitable securing means. In the 90 web portion 2 of the blank, however, the elements 3 are spaced apart. Those of the elements 3 in that part of the hub portion 1 to which the web portion 2 attaches are made alternately of small diameter and of sufficiently large diameter to extend up 95 through the web portion 2 to the point where the web joins the rim portion 6. The spaces intermediate the elements in the web portion 3 are occupied by the bakelite or other synthetic resin in its hard infusible 100 state, and this may be either in the form of the gum alone or in the form of the laminated gum impregnated structure previously described. In this instance, the rim or tooth-receiving portion 6 is preferably com- 110

- posed entirely of a laminated gum impregnated body, webs of paper or fabric being employed to form this laminated portion in the manner previously described, and the portion 6 being closely bonded or integral with the gum in the web portion 2. Those parts of the disks 3 extending into the web are preferably apertured for the purpose previously described.
- 10 In the embodiment of Fig. 3, plates or disks 3 are utilized only in the hub portion 1, the web 2 and rim 6 of the blank being formed preferably of the laminated artificial resin body previously described comprising webs of paper, fabric or other suitable fibrous material impregnated and bonded together by the artificial resin, which after impregnation and assembly has been converted to its hard infusible state.
- 20 Obviously there are many other modifications that may be made without departure from the invention in its essential features. Under some circumstances, it may be desirable to employ wire mesh, as illustrated in Fig. 5, in place of the metal disks illustrated in Fig. 4. In this instance, the resin or other material will extend completely through the entire gear and into the hub portion as well as the rim and web por-

tions. Under these circumstances, it is possible to eliminate the bolts 4 or analogous parts. In the modifications described, the plates 3 may be perforated throughout and the gum extended into the hub portion as well as to the other parts of the gear. It will also be apparent that portions of the hub illustrated as made up of disks may consist of integral bodies of metal properly shaped, and the invention is not limited to the use of metal plates or disks alone. 40

I claim:

1. A gear comprising a metal hub portion and a non-metallic toothed portion including a synthetic resin in hard infusible and insoluble condition reinforced by metal extensions from said hub. 45
2. A gear having a hub comprising a plurality of metal disks, and a toothed portion of sound-reducing material surrounding and bonded with the outer edges of said disks. 50
3. A gear comprising a plurality of metal discs, mechanical means binding the discs together at the hub, the outer portions of the disks being perforated, and an artificial resin body surrounding and embedding said outer perforated portions. 55

JOHN M. TAYLOR.
